ICE CREAM SPADE

Monte Levin, Roslyn Heights, N.Y., assignor to Rudi Baer, doing business as Progressus Company, New York, N.Y.

Filed Feb. 1, 1968, Ser. No. 10,394

Term of patent 14 years

Int. Cl. D7—03

U.S. Cl. D44—29

I claim:

The ornamental design for an ice cream spade, as shown.
